A photograph of a handwritten document titled "Peter Pan" in large, bold letters. Below the title, there is a small circular stamp with the text "Peter Pan" and "1962". To the left of the title, there is a drawing of a bird, possibly a pelican, with its beak open. The document is filled with handwritten text and some printed text from a template. The printed text includes sections like "Main page", "Contents", "Current events", "Random article", "About Wikipedia", "Donate", "Contributors", "History", "Learn to edit", "Community portal", "Recent changes", "Upload files", "Tools", "What links here", "Related changes", "Special pages", "Print/export", "Page information", "Cite this page", "What other items share this page?", "Wikidata item", "Wikisource", "Download as PDF", "Printable version", and "Go to media?". There are also sections for "Peter Pan" and "Wendy" with their own sub-sections. The handwriting is in cursive, and the overall layout is a mix of handwritten and printed text.
